tion of Delaware

Application May 28, 1930, Serial No. 456,513

8 Claims. (Cl. 123—179)

This invention relates to improvements in ignition devices for internal combustion engines.

It is among the objects of the present invention to provide an ignition device adapted to facilitate 5 starting of the engine.

Another object of the present invention is to provide an ignition device in which the primary circuit of an ignition coil is controlled to provide a more intense sparking impulse during the engine cranking operation than while the engine is 10 self-operating, thereby facilitating the starting operation.

Further objects and advantages of the present invention will be apparent from the following description, reference being had to the accompanying drawing, wherein a preferred embodiment of one form of the present invention is clearly shown.

In the drawing:

Fig. 1 is a side view of the ignition coil, the 20 spool including the windings being shown in section.

Fig. 2 is a plan view of the ignition coil, the spool including the windings being shown in section.

Fig. 3 is a diagrammatic view showing the 25 various elements of the device and their electrical connections.

Fig. 4 is a view similar to Fig. 3, showing however, a modified form of the ignition device.

The ignition device of the present invention 30 includes an ignition coil which has a field frame 20 made up of laminations and which provides a core 21 also constructed of laminated, magnetic material. Upon this core is supported the spool 35 of the ignition coil which includes the primary winding 23 and the secondary winding 24. A resistance winding 25 is connected in series with the primary winding 23 of the ignition coil.

The ignition device also includes a distributing 40 element 26 to which the secondary winding 24 is connected. This distributing element directs the sparking impulses from the ignition coil to the proper engine cylinders. A circuit interrupter or controller 27, driven by the engine, has one side 45 thereof connected to the primary winding 23 through the wire 28, the other side of said circuit interrupter being connected with the ground 30.

An electromagnetic switch is provided in 50 connection with the ignition coil, said switch comprising a bracket 35 having an arm 36 supporting stationary contact 37. This arm 36 is properly insulated from the bracket 35. A spring blade 38 carries the movable contact 39, said spring 55 being attached to the magnetic field frame 20 of

the coil so that said field frame provides also a magnetic field for the electromagnetic switch. On the bracket 35 there is carried a core 40 provided with a winding 41. One end of this winding is electrically connected with the bracket 35, the other end with the arm 36. It will be noted that spring blade 38 normally maintains its contact 39 in engagement with the contact 37 so that the resistance winding 25 which, as is shown in Fig. 3, is connected across the contacts 37 and 39, is 60 normally short circuited by said closed contacts. 65

The engine is provided with a starting motor 50, one side of which is connected with the storage battery or source of current 51 through wire 52, the other side of said motor being connected 70 to one side of the starting motor switch 53, which is grounded also as at 30. One side of the battery is grounded as at 30. A generator 55, adapted to be driven by the engine, is connected to one side of the cutout relay 56, the other side 75 leading to the battery 51 through the wire 57. The opposite side of the generator is grounded as at 30. The generator has a field winding designated by the numeral 58. The wire 57 leading from the battery 51 is connected to one side of the ignition switch 60 through the wire 61, the other side of said switch being connected through wire 62 with the arm 36 supporting the stationary contact 37 of the electromagnetic switch.

The object of this invention, as has been 85 stated, is to facilitate starting. In the present invention this is done by cutting a resistance winding out of the primary circuit of the ignition coil during the cranking operation, said resistance when in circuit with the primary winding of the 90 one coil substantially choking the flow of current through said primary circuit. When the operator wishes to start his engine, switch 60 is closed to connect the storage battery with the ignition coil. The starting switch 53 will then be closed, 95 permitting current to flow from the battery 51 through wire 52, motor 50, across the switch 53 back to the battery via the ground connections 30. Rotation of the motor 50 will crank the engine. The following ignition circuit will be established: from the battery 51 through wires 57 and 61, across the switch 60, through wire 62, across the contacts 37 and 39, spring blade 38 which is insulated from the core 21 of the coil, through the primary winding 23, wire 28, across 105 the circuit interrupter 27 back to the battery via the ground connections 30. The winding 41 of the electromagnetic switch is also in circuit, the wire 62 being connected with arm 36, one side of the coil 41 being connected to this arm also, while 110

the other side of the coil 41 is connected to bracket 36 which engages the grounded magnetic field frame 20 of the coil. When the battery 51 is discharging through the electric motor 50 for starting purposes, the voltage impressed upon the coil 41 is insufficient to energize said coil to attract and move the spring blade 38 so that its contact 39 will disengage with the contact 37.

As soon as the engine has become self-operating, the generator 55 will be driven to charge the battery 51, the starting of the engine signaling the operator to release the switch 53 to open the motor circuit.

Now the generator is impressing upon the coil 41 through the wire 61, switch 60 and wire 62, through arm 36, a sufficient voltage to energize said coil to attract the spring blade 38 and move its contact 39 out of engagement with the contact 37. When contacts 37 and 39 are thus separated, the short circuit about the resistance winding 25 is destroyed, thereby the current flowing from the source of energy to the primary winding 23 of the ignition coil must pass through the resistance winding 28 which acts as a ballast for the primary circuit.

In the Fig. 4 a modified form of the invention is disclosed. Here the primary circuit of the ignition coil has two windings 70 and 71, the first being the main winding, the latter an auxiliary winding. A resistance winding 72 is in series with the main primary winding 70. The auxiliary winding 71 is normally maintained in the circuit by the closure of the contacts 73 and 74 of the electromagnetic switch. In this instance when the ignition switch 75 is closed, the battery 51 will be in circuit with both primary windings 70 and 71 of the ignition coil. The closing of the starter switch 53, to operate the motor 50 for cranking purposes, will render the ignition switch 40 ineffective to open the contacts 73 and 74 during the cranking operation, and consequently both primary windings 70 and 71 cooperate to provide an intense, hot spark for starting purposes.

As soon as the engine has become self-operative, and is driving the generator 55, and the electric motor 50 is out of the circuit, a sufficient voltage will be impressed upon the winding 76 of the electromagnetic switch so that contact 74 will be moved out of engagement with its cooperating contact 73 and thus the circuit through the auxiliary primary winding 71 is broken and consequently only the primary winding 70 with its resistance winding 72 will operate to provide sparking impulses.

From the foregoing it may be seen that applicant has provided an ignition device in which an electromagnetic switch operates automatically to control the ignition device for starting and running conditions. During the starting operation the electromagnetic switch is rendered ineffective to break a short circuit or to reduce the turns of the primary circuit, however, as soon as the engine has become self-operating and the starting circuit is closed, this electromagnetic switch will operate automatically to break the short circuit about the resistance winding or to reduce the turns of the primary winding for such running operation.

The electromagnetic switch is so constructed and combined with the ignition coil that a portion of the ignition coil forms a portion of the electromagnetic switch, that is, the magnetic field of the ignition coil forms also a magnetic field for the electromagnetic switch.

75 While the form of embodiment of the present

invention as herein disclosed, constitutes a preferred form, it is to be understood that other forms might be adopted, all coming within the scope of the claims which follow.

What is claimed is as follows:

1. An ignition device for an internal combustion engine comprising, in combination, a source of current; an ignition coil having a magnetic frame supporting a primary winding; a resistance winding connected to the primary winding; a circuit controller for intermittently connecting the primary winding with the source of current; a secondary winding joining the primary between it and the circuit controller, so that the primary and secondary will be in series relation with the current source when the circuit controller interrupts the primary circuit, an electromagnetic switch having a movable armature carrying one of two normally closed contacts for by-passing the resistance winding, and a magnetic core, said switch being supported by the frame of the ignition coil so that the said frame provides a magnetic field for the switch, said switch being energized to open the contacts so as to prevent the by-passing of the resistance winding only during self operation of the engine.

2. An ignition device for an internal combustion engine comprising, in combination, a source of current; an ignition coil having a magnet frame, windings for two primary circuits carried by the frame; a resistance winding connected into one of the primary circuits; two normally closed contacts in the other primary circuit; a circuit controller for connecting both primary circuits with the source of current intermittently; and means for opening one of the primary circuits during self operation of the engine including an electromagnet mounted on the said frame, and operable to move one of the contacts.

3. An ignition device for an internal combustion engine comprising, in combination, a source of current; an ignition coil having a primary circuit including two primary windings connected in parallel; a core member for the coil supporting the windings; a resistance in series with one of the primary windings; a circuit controller for connecting the primary circuit of the ignition coil to the source of current; and an electromagnetic switch normally closed to complete circuit connections through the primary winding not in circuit with the resistance during engine starting and adapted to break the circuit through said winding during self operation of the engine.

4. An ignition device for an internal combustion engine comprising, in combination, a source of current; an ignition coil having primary windings in parallel with each other and in series with a secondary connected thereto; a resistance in series with one of the primary windings; and means for by-passing said resistance during the engine cranking operation said means including a pair of normally closed contacts in the circuit of the other primary winding, and an electromagnet operable to open said contacts, said electromagnet being responsive to voltage pressure through the ignition coil when the coil only is connected with a source of current.

5. An ignition device for an internal combustion engine comprising, in combination, a source of current; a transformer having a primary winding, and a secondary winding connected thereto, a resistance joining them to the said source; a booster winding in parallel with one of said windings; and means for temporarily inserting the booster winding in the primary circuit during

the engine cranking operation said inserting means comprising a pair of separable contacts in circuit with the booster winding, and the electromagnet operable upon one of the contacts, and 5 means for energizing the electromagnet when the transformer alone is operatively connected with the current source.

6. In an electrical system for an automotive engine having an ignition circuit, a starting motor circuit, and a source of current supply common to both circuits the combination of, means 10 providing parallel branches of widely different ampere-turns in the ignition circuit, and means for utilizing the branch of greater ampere-turns 15 coincident with closing of the starting motor circuit, said utilizing means comprising a pair of contacts inserted in one of the branches, an electromagnet whose armature carries one of the contacts to open the same, and means for energizing the electromagnet only when the starting motor circuit is open.

7. An electrical system for an internal combustion engine comprising in combination, a current source, a starting motor circuit energized from 25 said source, an ignition circuit energized from the same source and providing a primary path including an intermediate portion having two branches in parallel, a circuit controlling device for interrupting the primary path, a resistance 30 in one of the parallel branches, a pair of sep-

arable contacts in the other branch, means yieldingly maintaining the contacts in engagement so as to by-pass the resistance when the starting motor circuit is closed, and means for opening the contacts when the starting motor circuit is opened and the ignition circuit is closed so as to reduce the number of ampere-turns in the ignition circuit while the engine is running.

8. An electrical system for an internal combustion engine comprising in combination, a current source, a starting motor circuit energized from said source, an ignition circuit energized from the same source and providing a primary path including an intermediate portion having two branches in parallel, a circuit controlling device for interrupting the primary path, a resistance in one of the parallel branches, a pair of separable contacts in the other branch, means yieldingly maintaining the contacts in engagement so as to by-pass the resistance when the starting motor circuit is closed, and means for opening the contacts when the starting motor circuit is opened and the ignition circuit is closed so as to reduce the number of ampere-turns in the ignition circuit while the engine is running, said contact opening means comprising an electromagnet whose winding is operatively energized only when the starting motor circuit is opened and the ignition circuit is closed.
